(Cl. D71—1)

To all whom it may concern:

Be it known that we, Derwood A. Beck and Edwyn A. Eddy, both citizens of the United States, residing at Seville, county of Medina, and Massillon, county of Stark, respectively, and the State of Ohio, have invented a new, original, and ornamental Design for an Airplane, of which the following is a specification, reference being had to the accompanying drawings, forming part thereof.

Fig. 1 is a top plan view of an airplane showing our new design.

Fig. 2 is a front elevational view.
Fig. 3 is a side elevational view, and

Fig. 4 is a rear elevational view.

We claim:

The ornamental design for an airplane, as shown.

DERWOOD A. BECK.
EDWYN A. EDDY.
